17 Claims. (Cl. 1-11)

The present invention relates to wire stitching machines for stitching cardboard cartons or boxes and is more particularly concerned with the type of machine used for progressively stitching corrugated cardboard cartons.

In the manufacture of cartons of the larger dimensions for transit purposes, use has been made more recently of foldable boxes produced from corrugated cardboard. Such cartons, when collapsed, occupy a comparatively small space. The stitching of these cartons was hitherto confined to the use of flat wire stitching machines. The carton was collapsed as required and placed on a horizontal arm of the machine, said arm containing the tools for clinching over the staple legs, and after completion of the stitching, had to be withdrawn again. In order to obviate the manual removal of each completed carton from beneath the stitcher head the so-called progressive stitching has been resorted to, according to which the collapsed cardboard carton to be stitched is so placed on a feed table, provided on the machine, that one of the overlapping closing ends of the box is positioned just above and the other below the dividing portion of a suitably shaped tongue, arranged above the feed table. Subsequently, during the progress of the carton to the stitcher head, both ends are brought together and then pass over the clincher member. Consequently, it is possible, in progressively stitching the cartons, to cause the latter to pass along the feed table to the stitcher head, and when stitched, to continue through and to be ejected at the further side of the feed table. In dealing with corrugated cardboard cartons in a wire stitching machine it is sometimes desirable to position the staples obliquely to the corrugations in order that the legs of such staples, when clinched over may lie in two different corrugation tracks of the cardboard.

The object of this invention is to provide a wire-stitching machine whereby stitches may be progressively inserted with particular advantage in corrugated cardboard boxes or cartons at any desired angle to the corrugation tracks of the work by a mere variation of the direction of its travel through the machine.

To this end according to the invention, the machine which, as shown by way of example, may be of the treadle controlled type and having a stitcher head in a permanently set position, is provided with mechanism enabling by simple adjustment the direction of travel of the work to be readily varied whereby a collapsed corrugated cardboard carton may be caused to

be guided beneath the stitcher head with its corrugation tracks parallel to or at any predetermined angle to the position of the stitches to be applied thereto.

The above and other features of the invention will be more readily understood by reference to the accompanying drawings which illustrate one embodiment thereof in a suitable stitching machine, in which:

Fig. 1 shows the stitching machine in side elevation.

Fig. 2 is a front elevation thereof.

Figs. 3 and 4 show the stitcher tongue and box guides set in the straight and oblique stitching positions respectively.

Fig. 5 is a detail view showing the means for attaching the stitcher tongue to the supporting bracket.

Fig. 6 is a side elevational view of the adjustable treadle, and

Fig. 7 a plan view thereof.

Referring to Figs. 1 and 2, the main frame 10 of the wire-stitching machine supports a wire-stitcher head 11 of known type which in this embodiment is power driven and controlled in the usual manner by a tripping clutch operated through the linkage 12, from the treadle 13. A box support 14 of known design extends horizontally from the main frame 10 to beneath the stitcher head 11. A feed table 15 is detachably fitted upon the member 14 and sheet or box guides 16 adjustably mounted thereon. A stitcher tongue 17 supported at one end thereof from the main frame 10, to one side of the stitcher head, as shown in Fig. 2, extends transversely of the feed table between the guides 16 and terminates beneath the stitcher head 11. The supported end of the tongue 17 is provided with an upwardly extending flange 18 which is secured by readily releasable means to a supporting bracket 19. The flange 18 is attached to the tongue 17 so as to form a ledge 17a which is clearly spaced from the surface of the tongue (Fig. 1). The extremity of the member 18 is flared out to form a mouth 18a (Fig. 2).

Referring more particularly to Figs. 3, 4 and 5, the bracket 19 is formed by a centre hub 20, attached to the main frame by means of a downwardly extending arm 21. The hub 20 carries two arms 20a and 20b which, preferably are of circular cross section and have their outer extremities drilled and threaded to receive a locking screw 22a. The arm 20a is set parallel to the support 14 whilst the arm 20b is set obliquely thereto in the same horizontal plane. The flange 110

18 attached to the tongue 17 is formed integral with a collar 22 which slidably fits upon either arm 20a, 20b, and is held thereon by means of the locking screw 22a. The clincher mechanism 5 23 is set within a circular casing which is rotatably mounted upon the free end of the tongue 17 directly beneath the stitcher head. The guides 16 are provided with slotted lugs by which they are adjustably bolted to the feed table. Instead 10 of effecting the setting of the tongue 17 by fitting it on to the requisite arm 20a or 20b its pivot could be arranged on a separate bearing (not shown) adapted to be screwed to the frame at requisite points.

15 The control treadle 13 (Figs. 6 and 7) is secured to side shanks 24 which are adjustably held in clamping members 25. The latter are pivotally mounted at the base of the machine frame and the shanks 24 are held therein by means of 20 set screws 25a.

23 The operation of the stitch positioning mechanism is as follows:

If the machine is to be used for progressively positioning staples parallel to the line of corrugation of the collapsed cardboard carton, the 25 mechanism is positioned as shown in Figs. 1, 2 and 3. That is to say, the stitcher tongue 17 is mounted upon the arm 20a and held thereon by means of the screw 22a. The guides 16 are set 30 parallel to the longitudinal axial line of the tongue 17 which, mounted as above described, is rotatable about the axis of its supporting arm 20a. The collapsed cardboard carton is then placed on the feed table to the left-hand side of 35 the stitcher head (Figs. 2 and 3) so that the lower of the two overlapping edges to be stitched is positioned on the tongue 17 and the upper edge 17a. Upon being progressed toward the stitcher head in the direction of travel indicated by the 40 arrow A, the edges move clear of the ledge 17a and come together to lie upon the clincher mechanism beneath the stitcher head, and so receive a stitch or stitches parallel to the line of corrugation.

45 It will now be clearly seen that in order to position staples in, for instance, a corrugated cardboard carton, at an angle to the corrugations the necessary adjustments are very readily made.

The winged headed screw 22a is removed and 50 the tongue 17 removed from the arm 20a, and mounted upon the arm 20b being locked thereon by means of the screw 22a. The tongue 17 is now positioned at an oblique angle to the stitcher head (Fig. 4). The guides 16 are swung round 55 to lie parallel to the adjusted longitudinal axial line of the tongue, and the clincher mechanism readjusted above its vertical axis to register correctly with the stitcher head stapling mechanism. Since, by the adjustment above described, the 60 feed end of the tongue now stands further forward from the machine, the operator may have to change position accordingly. If this is necessary the control treadle 13 is conveniently brought within reach of this altered position by slackening the set screw 25a and adjusting the 65 shanks 24 as required. The collapsed cardboard carton, positioned on the feed table and tongue 17 as above described, is now progressed toward the stitcher head in the direction of travel indicated by the arrow "B" i. e., at an angle to the 70 horizontal position of the stitches or staples to be inserted therein.

If the cardboard is corrugated, each leg of the 75 staple is thus clinched over to lie in a separate corrugation track, whilst the head of the staple

is positioned obliquely to the line of corrugation.

In order to utilize this machine for the more usual type of cardboard box stitching, the stitcher tongue and feed table may be readily removed and the box support 14 fitted with the clincher 80 mechanism in the known manner.

I claim:

1. In a machine for wire-stitching cardboard cartons or boxes in combination, a stitcher head, a box support, side guides for the boxes associated with the box support, means for angularly adjusting said side guides, a stitcher tongue and means for varying the angular position of said stitcher tongue relatively to the said stitcher head. 85

2. In a machine for wire-stitching cardboard cartons or boxes in combination, a stitcher head, a box support, a work table mounted on said box support, side guides adjustably mounted on said work table, a stitcher tongue, a supporting bracket, carrier arms on said supporting bracket set at an angle one to the other, means for rotatably mounting said stitcher tongue on the arms as required, clincher mechanism, and means for adjusting said clincher mechanism in relation to the 90 stitcher tongue.

3. In a machine for wire-stitching cardboard cartons or boxes in combination, a main frame, a stitcher head supported from said main frame, a box support, a stitcher tongue above said box support, means for supporting the stitcher tongue 105 at one end from the said main frame, and means for varying the angular position of said stitcher tongue relatively to the stitcher head.

4. In a machine for wire-stitching cardboard cartons or boxes in combination, a main frame, 110 a stitcher head supported from said main frame, a box support, a work table mounted on said box support, side guides mounted on said work table, a stitcher tongue, a supporting bracket for said stitcher tongue attached to the said main frame, 115 means for mounting said stitcher tongue upon said bracket, means for varying the angular position of said stitcher tongue, and means for adjusting said side guides longitudinally parallel each to the other for the purpose set forth. 120

5. In a machine for wire-stitching cardboard cartons or boxes in combination, a main frame, a stitcher head supported from said main frame, a box support, a work table mounted on said box support, side guides adjustably mounted on said 125 work table, a stitcher tongue, a supporting bracket for said stitcher tongue attached to said main frame, means for rotatably mounting said stitcher tongue upon said bracket, means for varying the angular position of the said stitcher tongue relatively to the stitcher head, clincher mechanism mounted upon the free end of said tongue, means for positioning said stitcher tongue and said side guides longitudinally parallel each to the other, and means for positioning the clincher mechanism 130 in correct working relation to the said stitcher head for the purpose set forth.

6. In a machine for wire-stitching cardboard cartons or boxes, in combination, a stitcher head, means for controlling the actuation of said stitcher head, means for guiding work as it progresses past the said stitcher head, means for varying the direction of travel of said work past the stitcher head, and means for adjusting the said stitcher head control in accordance with the direction of 140 progression of the said work.

7. In a machine for wire-stitching cardboard cartons or boxes, in combination, a stitcher head, a treadle member adapted to control said stitcher head, means for guiding work as its progresses 145

- past the stitcher head, means for varying the direction of progression of said work, and means for adjusting the position of the said treadle control for the purpose set forth.
- 5 8. In a machine for wire-stitching cardboard cartons or boxes, in combination, a stitcher head, a box support, a stitcher tongue, means for adjusting in the horizontal plane the angular position of the tongue relatively to the stitcher head, a clincher mechanism, and means for adjusting said clincher mechanism in relation to the respective positions of the said stitcher tongue and stitcher head. 80
- 10 9. In a machine for wire-stitching cardboard cartons or boxes, in combination, a stitcher head, a box support, a stitcher tongue rotatably supported above said box support, means for adjusting in the horizontal plane the angular position of the said stitcher tongue, clincher mechanism carried on one end of said stitcher tongue, and means for adjusting the position of said clincher mechanism in relation to the respective positions of the said stitcher tongue and stitcher head. 85
- 15 10. In a machine for wire-stitching cardboard cartons or boxes, in combination, a stitcher head, a box support, a work table mounted on said box support, side guides pivotally mounted on said work table, a supporting bracket positioned above said box support, carrier arms on said supporting bracket set at an angle one to the other, a stitcher tongue, means for mounting said stitcher tongue on either of said arms as required, clincher mechanism mounted on one extremity of said stitcher tongue, and means for adjusting the position of said clincher mechanism relatively to the respective positions of the said stitcher head and said stitcher tongue. 90
- 20 11. In a machine for wire-stitching cardboard cartons or boxes, in combination, a main frame, a stitcher head supported from said main frame, a box support, a stitcher tongue immediately above said box support, means for adjustably supporting said stitcher tongue at one end from the said main frame, clincher mechanism mounted upon the free end of said stitcher tongue, means for adjusting said stitcher tongue about an axis of the said clincher mechanism, and means for adjusting said clincher mechanism in relation to the positions of the 95 said stitcher tongue and stitcher head.
- 25 12. In a machine for wire-stitching cardboard cartons or boxes, in combination, a main frame, a stitcher head supported from said main frame, a box support, a work table mounted on said box support, side guides pivotally mounted on said work table, a supporting bracket positioned above said box support, carrier arms on said supporting bracket set at an angle one to the other, a stitcher tongue immediately above said box support, means for adjustably supporting said stitcher tongue at one end from the said main frame, clincher mechanism mounted upon the free end of said stitcher tongue, means for adjusting said stitcher tongue about an axis of the said clincher mechanism, and means for adjusting said clincher mechanism in relation to the positions of the 100 said stitcher tongue and stitcher head.
- 30 13. In a machine for wire-stitching cardboard cartons or boxes, in combination, a main frame, a stitcher head supported from said main frame, a box support, a work table mounted on said box support, side guides pivotally mounted on said work table, a supporting bracket positioned above said box support, carrier arms on said supporting bracket set at an angle one to the other, a stitcher tongue immediately above said box support, means for adjustably supporting said stitcher tongue at one end from the said main frame, clincher mechanism mounted upon the free end of said stitcher tongue, means for adjusting said stitcher tongue about an axis of the said clincher mechanism, and means for adjusting said clincher mechanism in relation to the positions of the 105 said stitcher tongue and stitcher head.
- 35 14. In a machine for wire-stitching cardboard cartons or boxes, in combination, a main frame, a stitcher head supported from said main frame, a box support, a work table mounted on said box support, side guides pivotally mounted on said work table, a supporting bracket positioned above said box support, carrier arms on said supporting bracket set at an angle one to the other, a stitcher tongue immediately above said box support, means for adjustably supporting said stitcher tongue at one end from the said main frame, clincher mechanism mounted upon the free end of said stitcher tongue, means for adjusting said stitcher tongue about an axis of the said clincher mechanism, and means for adjusting said clincher mechanism in relation to the positions of the 110 said stitcher tongue and stitcher head.
- 40 15. In a machine for wire-stitching cardboard cartons or boxes, a machine frame, a stitcher head supported from said frame, a work table, a stitcher tongue supported at one end and having its free end extending beneath said stitcher head, clincher mechanism mounted on the free end of said stitcher tongue, and means for adjusting said stitcher tongue about the vertical axis of said clincher mechanism. 115
- 45 16. In a machine for wire stitching cardboard cartons or the like, in combination, a stitcher head, a work support beneath said stitcher head, a stitcher tongue positioned between said stitcher head and said work support, clincher mechanism mounted upon said stitcher tongue, and means for adjusting said stitcher tongue angularly about the vertical axial line of said clincher mechanism and independently of said work support. 120
- 50 17. In a machine for wire stitching cardboard cartons or the like, in combination, a stitcher head, a work support extending beneath said stitcher head, a stitcher tongue mounted above said work support and independently thereof, clincher mechanism carried by said stitcher tongue and located on the vertical axial line of said stitcher head, and means for adjusting said stitcher tongue angularly about said vertical axial line. 125

OSCAR KLEINSCHMIT.
